UNITED STATES PATENT OFFICE.

WILBER C. BELKNAP, OF NEW YORK, N. Y., ASSIGNOR TO ROBERT E. MILLER, INC., OF NEW YORK, N. Y., A CORPORATION OF NEW YORK.

RUBBER HEEL.

1,324,993.

Specification of Letters Patent. Patented Dec. 16, 1919.

Application filed September 16, 1918. Serial No. 254,201

To all whom it may concern:

Be it known that I, WILBER C. BELKNAP, a citizen of the United States, residing at New York, in the county of New York and State of New York, have invented certain new and useful Improvements in Rubber Heels, of which the following is a specification, reference being had therein to the accompanying drawing.

10 This invention relates to improvements in rubber heels to be attached to the leather heels of shoes.

The particular object of the invention is to more effectually prevent slipping, and 15 this object is carried out by constructing the rubber heel with a central depressible portion whose upper surface forms an elevated portion adapted to be depressed by the leather heel when the rubber heel is 20 secured thereto and which depression acts in turn to depress the lower surface somewhat below the lower face of the remainder of the rubber heel. In this way the connecting of the rubber heel with the leather heel 25 brings about the projection downward of the depressible portion.

In carrying this object into effect I also get the further result of a more elastic heel since this depressed portion, being protruded 30 slightly below the general lower face of the rubber, increases the resiliency.

It is common to recess the lower part of a rubber heel with a view of causing a sort of "suction" action to retard slipping. But 35 that also retards the free lifting of the heel from the walking surface. My invention is the direct reverse of this construction and is free of this retarding effect on the lifting of the heel.

40 In the accompanying drawings forming a part of the specification, Figure 1 is a perspective view of the lower face of my improved rubber heel; Fig. 2 is a like view of the upper surface of such heel; and Fig. 3 45 is a vertical sectional view of the rubber heel and the leather heel of a shoe, showing the two heels attached together.

The numeral 1 designates my improved rubber heel generally, it being made of the 50 usual or any approved rubber compounds to give the requisite strength and the desired resiliency. It has a series of openings 2 through which the fastening devices, as brads, are extended when driven into the 55 leather heel of the shoe. These are ordinary

features. In the body of the rubber heel, preferably substantially central, I form a portion which I will designate as a depressible gripping section 3. This section is fashioned on its upper face, preferably, in 60 the form of a cone so that the apex or point will contact with the bottom of the leather heel when the two heels are united. This contact will slightly depress the section 3, causing its lower surface to protrude slightly 65 below the lower surface of the remainder of the rubber heel. This is very clearly shown in Fig. 3.

The lower surface of section 3 is configured in a manner to increase its grip, as also 70 to add to its resiliency. The preferred configuration is that of a series of points or miniature pyramids inverted, as indicated at 4. These pointed portions will be projected slightly below the lower level of the rubber heel by the connection of the rubber heel to the leather heel, as before stated. This slight projection causes the succession of points to contact severely with the walking surface and then when the weight of the 80 wearer comes down on the heel the depressible portion is further pressed downward so that the succession of points more or less flatten by the successive pressure contact of the walking surface. This is shown in 85 Fig. 3.

Accordingly, by my improved rubber heel I have attained the important primary result of increased gripping of the heel to the pavement or walking surface in a manner that operates to prevent slipping. This increased gripping is effected primarily, by the slight depression of the depressible surface by the connection of the rubber to the leather heel. It is further increased by the 90 weight of the wearer. And incidentally the resiliency of the heel is increased because this protruding portion of limited area will the more readily yield.

I have referred to the upper surface of 100 the depressible section as cone shaped, but any other outline will serve the purpose so long as the functions indicated are obtained.

Having thus fully described my invention, what I claim as new and desire to secure by 105 Letters Patent, is:

1. A new article of manufacture comprising a rubber heel having a body portion adapted to be secured to a solid heel and having an outer recess occupied by a tread 110

portion and an inner recess opposite the outer recess occupied by a projection adapted to contact with the solid heel, whereby said tread portion will be normally projected below the tread surface of said body portion when the rubber heel is secured to the shoe.

2. A new article of manufacture comprising a rubber heel having a body portion adapted to be secured to a solid heel and having an outer recess occupied by a gripping tread portion and an inner recess opposite the outer recess occupied by a tapered projection adapted to contact with the solid heel, whereby said tread portion will be normally projected below the tread surface of

said body portion when the rubber heel is secured to the shoe.

3. A new article of manufacture comprising a rubber heel having a body portion 20 adapted to be secured to a solid heel and having a central gripping tread portion consisting of a plurality of rows of miniature pyramids and an inner recess occupied by a conical projection opposite said tread portion 25 adapted to contact with the solid heel, whereby said tread portion will be projected below the surface of said body portion when the rubber heel is secured to the shoe.

In testimony whereof I affix my signature. 30

WILBER C. BELKNAP.
